(57) **CLAIM**

The ornamental design for a skin massage roller, as shown and described.

DESCRIPTION

FIG. 1 is a perspective view of a skin massage roller, showing my new design;

FIG. 2 is a front view thereof, a rear view being a mirror image;

FIG. 3 is a left side view thereof;

FIG. 4 is a right side view thereof;

FIG. 5 is a top view thereof; and,

FIG. 6 is a bottom view thereof.

The broken lines shown are included for the purpose of illustrating the unclaimed portions of the skin massage roller and form no part of the claimed design.
